UNITED STATES PATENT OFFICE.

ALFRED ALLEN, JOHN J. MURPHY, AND HARRY A. WILLARD, OF TOLEDO, OHIO,
ASSIGNORS, BY MESNE ASSIGNMENTS, TO THE PAN CHRO SCOPE CORPORATION,
OF INDIANAPOLIS, INDIANA, A CORPORATION OF INDIANA.

MULTICOLOR STEREOSCOPIC DEVICE.

1,281,746.

Specification of Letters Patent. Patented Oct. 15, 1918.

Application filed December 13, 1915. Serial No. 66,468.

To all whom it may concern:

Be it known that we, ALFRED ALLEN, JOHN J. MURPHY, and HARRY A. WILLARD, citizens of the United States of America, 5 residing at Toledo, Lucas county, Ohio, have invented new and useful Multicolor Stereoscopic Devices, of which the following is a specification.

This invention relates to reproducing subjects as originally appearing.

This invention has utility when incorporated in views, and apparatus for facilitating the inspection thereof, to disclose the third dimension in the different colors thereof as 15 a commercial proposition for compact handling and shipment in little space at a minimum of expense for production, with simplicity for manipulation in use owing to absence of involved or technical features.

20 Referring to the drawings:

Figure 1 is a perspective view of an embodiment of the invention, with parts broken away, shown in set up assembled position for use;

25 Fig. 2 is a front elevation of a stereoscopic view comprising color value elements of dissimilar colors in fields of such colors, as adapted for use in the device of Fig. 1;

Fig. 3 is a perspective view in partially 30 collapsed position of the first tube of the stereoscope device of Fig. 1;

Fig. 4 is a perspective view in partially collapsed position of the second tube of the stereoscope of Fig. 1;

35 Fig. 5 is a perspective view in partially collapsed position of the third tube of the stereoscope of Fig. 1; and

40 Fig. 6 is a side elevation of the pair of stereoscopic lenses for mounting in the tube of Fig. 5.

The simplicity of the device is such that the elements thereof may be forwarded in knocked-down condition to the trade or users thereby minimizing space, with the device of light weight construction amply substantial to withstand normal usage in practice.

45 The stereoscope comprises the main member 1, being a tube of rectangular cross section having the end closure 2 slightly offset by the coacting flanges 3, 4, at the sides and 5 at the base to form a view receiving pocket when brought up to alined position as to the tube 1, and so firmly held by the locking

tongue 6 entering recesses 7 in the end closure 2. When so assembled, the end closure 2 tends to lock the tube 1 in set up position with the bottom and sides of the tube cutting off all light rays to a view placed against the end closure 2. 55

The top portion has the window or cut-back portion 8 approximately balancing the light ray illumination of a view as to the elements thereof, as inspected through the tube 1. This brings about a coöperating 60 function in synthesizing or combining the value colors for accurate and effective results.

The element 9 (Fig. 6) may have openings therein surrounded by the bent out 70 wings 10 to which may be attached by an adhesive the respective stereoscopic lens elements 11. This lens carrier 9 may be disposed to have the lenses 11 register with the openings 12 in the collapsible tube 13. Alining 75 with the openings 12 are the openings 14 which in the set-up position will have the wings 15 therefrom swung back into the tube and locked in such partition forming position by the tongue 16 engaging the recess 17. 80 The terminal flanges 18, 19, of the tube 13, are bent inward to assist in the frictional holding of this tube 13 in tube 20 and also lock carrier 9 in set up position. The tube 20 is thus held against collapse and is adjustable 85 in the tube 1 for ready focusing of the lenses 11 as to the view in the seat 2.

This view may comprise the element 20' having the color field 21, say of red, with the outline 22 in said field valued in red. 90 The corresponding stereoscopic element or view 23, from a spaced origin for stereoscopic effectiveness, may have its field 24 of color dissimilar to the color 21, say green, with the outline or image 25 valued in such 95 color.

In the operation to attain the articles of manufacture hereunder, a stereoscopic view may be taken with any pan-chromatic plate, say of the Lumiere type. Owing to 100 the different speed actions of the complementary or differing colors, this simultaneous taking for all of the colors has advantages, for with this multi-color plate, from one side thereof may be obtained the outline for, 105 say the color red, with proper developments for the strength desired. From the opposite side may be taken the outline, say for

the color green, developed for proper strength relatively to the outline from the color red. These two separately produced outlines from the basic plate may be printed 5 in adjacent positions for the regular stereoscopic view but each of these outlines in the projection of this stereoscopic view, as an integral article of manufacture, is disposed in a field of its color.

10 In the multiplication of these devices, they may be conveniently produced as half tones, at a single impression completing each view, by using say the red ink for the field and the outline, the strength of the field differing so there is the outline contrast. While in other operations, say as in printing from negatives, the field may be the stock color or the stock may be colored after the outline is developed thereon to produce a 15 unitary article of manufacture. The resulting operative device or element is, whether or not the outline is of black or of a color, a color value outline in a field of such color.

20 In practice, it is found the two colors mentioned are serviceable over a wide range for accurate reproduction of multi-color work with different shades and colorings beyond the two in the view as a result of inspection through the stereoscope herein, for 25 there is a synthesizing or re-combining approaching original appearance in all the original tints, shades and colors of the spectrum. The selection of the two field colors and corresponding values simplifies this 30 reproduction, not only for photographic but for printing purposes.

35 In some instances of special colored objects, it may be desirable to specially adapt the contrast colors for the view fields and the color valued outlines thereon. The instance herein of a strong color from one 40 end of the normal color spectrum, and a second strong color from the other region of the spectrum, due to the color spacing, shows up in a measure of practical commercial 45 worth, when combined for viewing in the stereoscope combination. In producing the views, the color 21 may be the color of the stock used or a coating on the stock, and outline 22 may be in black ink thereon over or 50 under a coating on the stock. Accordingly, the single black outlines on the dissimilar

fields or backgrounds may at one printing impression produce a view of spectrum disclosing effectiveness. This result from black ink is due to the color valued black 55 outlines and the stereoscopic blending of the backgrounds enhanced by the single direction light ray to the pictures being viewed.

What is claimed and it is desired to se- 60 cure by Letters Patent is:

1. A view having two outlines, one valued in one color and the other valued in a contrasting color, and corresponding fields of color for said outlines, whereby the eyes of 65 an observer may effect a composition of colors.

2. A third dimension and color disclosing view comprising two dis-similar color value outlines and corresponding fields of color 70 for said outlines.

3. A stereoscopic view including spaced origin color valued outlines, each having integral therewith a color valued field of such color.

4. A stereoscopic opaque picture comprising right and left hand views having complementary color values in fields of such color.

5. In a device for disclosing views in color 80 by reflected light, the combination with an opaque base of color outlines thereon in fields of complementary colors in union with said base.

6. In a device for disclosing more than 85 two colors by reflected light in views, the combination with an opaque base of complementary colored fields thereon, each of said fields embodying an outline therein, said colored fields and outline being fixed 90 with the base.

7. The combination in a picture disclosing a view, of an opaque base, and fixed with said base a color valued outline in a colored field.

8. The combination in a picture disclosing device, of a base providing a colored field fixed therewith and in said field an outline valued in the color of said field.

In witness whereof we affix our signatures. 100

ALFRED ALLEN.

JOHN J. MURPHY.

HARRY A. WILLARD.
